P. Edmunds

UNITED STATES PATENT OFFICE.

EMILY ANN WELLMAN, OF NEW YORK, N. Y.

METHOD OF AND APPARATUS FOR PRESENTING PLAYS AND THE LIKE.

Application filed December 6, 1919. Serial No. 342,959.

To all whom it may concern:

Be it known that I, EMILY ANN WELLMAN, a citizen of the United States, residing in the borough of Manhattan, city, county, and State of New York, have invented certain new and useful Improvements in Methods of and Apparatus for Presenting Plays and the like, of which the following is a specification.

10 The object of the present invention is to provide an improved method and apparatus for the presentation of plays, pantomimes, and the like, upon a theatrical stage. A further object of the invention is to make possible the use of a greater number of scenes in a play than has heretofore been attempted within a given period; to accomplish this easily and gracefully and without the consciousness of effort on the part of the audience, without the distraction of noises due to the shifting of cumbersome scenery, properties and the like, and without the artificiality of obvious effects, such as the lowering of drops, the drawing of curtains, etc.

20 25 In general, one plan upon which the invention may be carried into effect is as follows:

Extending around a substantial portion of the available area of a stage (and by "available area", I mean the portion which normally and with the usual front curtain raised is observable from the body of the theatre) is a curtain, screen, drop or the like (hereinafter termed a curtain), the forward portion of the area so partially enclosed being open in the direction of the body of the house. Projecting from such curtain inwardly toward the centre of the partially enclosed space are movable and preferably collapsible wings, and by "collapsible" here is meant that the same may be removed from their position of inward projection by any suitable means, as by moving them into parallelism with the curtain, folding them within narrow compass or removing them entirely behind the curtain. In their position of inward projection, these wings have the effect of subdividing the space available for the presentation of plays into a series of separated areas, hereinafter termed compartments, in each or certain of which light and portable scenery, properties, etc., may be erected or placed, the same being concealed, however, by such wings until it is desired to present the same.

55 For the curtain and for the wings, I preferably employ a dark, light-absorbing mate-

rial, for example, black velvet. Both curtain and wings may be formed of this material, suspended from overhead supports, or they may be rigid if desired; the advantage of the former being that the loose lower edge of both the curtain and the wings, and more particularly of the latter, is more readily adjustable, which is desirable when it becomes necessary to draw the same over mechanical properties, such as tables, chairs and the like, whose proper disposition in the space requires them to project beyond the area limited by the wings in their normal position.

Thus if, for example, the available area upon the stage be divided into five compartments, a scene may be set up in each compartment, all or all but one of these being concealed in the manner stated. An electric projector, of suitable character and power and having the usual diffusing device, is arranged adjacent to each end of the curtain, preferably so that each may illuminate the central area and the compartments in proximity to the opposite side of the curtain. In presenting a play, the usual stage curtain is raised, the house, including the stage, being dark. One of the projectors "picks up" one of the prearranged scenes (from in front of which the concealing wing has been removed), which alone is illuminated. This remains illuminated during the presentation, including dialogue, etc., if the play be of this character. At the conclusion of the scene, the area in question is darkened by obscuring the light, an another scene in another compartment (from which the wing has been removed) is illuminated, either by the same or the opposite light, so that the play proceeds practically without intermission and yet with the usual changes of scene, as well as change, if desired, in the players.

The scenery employed is portable and placed in the various compartments by means of openings through the curtain, which openings may also serve as the means of ingress and egress of the players. Preferably, background scenes are portrayed on light folding frames, adapted to be placed in position folded and then quickly opened to the position in which they are to be displayed. Preferably also, the folding portions of said scenes which will be nearest the audience when folded are, like the curtain and wings, of dark and light-absorbing material, such as black velvet. By the proper

manipulation of the projectors, one or another area or compartment may be illuminated at will, the rest of the stage being obscured. Also, while one area or compartment is being utilized, the scenery, properties, etc., in another may be changed or, if desired, wholly removed, and other scenery and properties substituted therefor.

A practicable method of carrying out the invention is illustrated in the accompanying drawings, in which Figure 1 is a top plan view illustrating curtain, wings, scenery, projectors, etc., as above referred to; Figure 2 is a partial elevation on the line 2—2 of Figure 1; and Figure 3 is a partial elevation of the opposite end of the curtain, looking in the direction of the arrows 3—3.

Referring to these drawings, 1 indicates a bow-shaped frame, here shown as constructed of tubing connected by suitable unions 2. This frame is hung from the flies in any suitable manner, as by ropes 3, of which there may be any desired number. From this frame depends what I have termed generically the curtain, 4. This is here shown as secured to the frame 1 by rings 5. Said curtain, as above stated, is preferably of black velvet, hanging in loose folds, its lower edge being in contact with the stage. 6, 6 designate tubular supports, upon which the (black velvet) wings may be mounted, as by means of rings. These are pivoted at 7 upon a suitable casting carried by the frame 1 and may be moved into the full line position in which they are illustrated or into a position practically parallel with the curtain (as, for instance, that shown in dotted lines in Figure 1), and this may be accomplished in any suitable manner, as by direct pressure or in the manner disclosed in the drawing, this involving the use of a sheave 8 for each of the supports 6, such sheave being operable from behind the curtain by means of a cord 9. It is, of course, apparent that instead of this, the supports 6 may have their free ends both swung and operated from the flies.

Adjacent to the forward ends of the curtain 4, I arrange additional wings, which are preferably jointed, as shown. These comprise tubular supports 10 and 11, pivoted at 12, the distant end of the support 11 being also pivoted at 13 upon a suitable casting carried by the frame 1. As with respect to the supports 6, the supports 10 and 11 may be either carried and moved from the flies or by hand by means back of the curtain 4. I have here shown each of the pivots 12 as associated with a sheave 14, and each of the pivots 13 as associated with a sheave 15, said sheaves being connected by the cord 16 and both being operated by the cord 17 from back of the curtain.

As will be seen, the arrangement of wings above described divides the area partially

enclosed by the curtain 4 into four compartments, which are available for the presentation of scenes, and in addition to this, also available for the same purpose, there is the "back stage" area, as well as the "up stage" area. Any one of these areas may be "picked out" by the projectors 18, 19, or one of them. It will also be seen that when one such area is thus illuminated, the others may be concealed, or, if preferred, unoccupied by scenery, properties and the like and forming, therefore, black background.

At 20, Figure 1, I have indicated portable scenery, here shown as consisting of a back 21, sides 22, and front members 23, the latter being hinged to the sides 22 and the sides to the back 21. The background may be displayed either by painting or attachment upon the inner surfaces of all of the parts 21, 22, 23, and preferably the outer surfaces of the parts 22, 23 will be covered with a black light-absorbing material, such as velvet. This portable background, as well as any properties (such as the chair 24), may be introduced through a slit in the curtain 4, there being such a slit adjacent to each of the several areas or compartments. On being introduced in folded form, the sides, or, if provided with ends, both the sides and ends, may be quickly opened out to full extent or such lesser degree as may be desired.

It should be understood that the upper portion of the apparatus described, including the supports for the curtains, wings, etc., will be covered by the usual drop curtain, and that the ends of the curtain, as well as the projectors, will be obscured from the body of the theatre by the usual drop legs.

The use of the wings as above described permits of the fullest utilization of the area at command and with the minimum intervals between scenes. For example, scenes may be set up in certain of the areas or compartments, one of these illuminated and immediately upon the conclusion of the act the lights shifted to another. Also, while the act at such latter point is in progress the scenery may be shifted or changed in the compartment formerly used. Both of the opposite compartments between the wings may be closed off by bringing, for example, the wings 6, 10 and 11 together, so as to completely enclose the area between them and thus make possible a scene mid-stage. Or such scene may be located back stage or up stage, no scene in any case being interfered with by the setting designed for another scene.

Having now described my invention, what I claim as new therein and desire to secure by Letters Patent is as follows:

1. The method of presenting plays and the like upon an immovable stage, which consists in setting up discrete scenes at different

- portions of the area at command and which area is normally open to view from the body of the theatre, and, the stage being dark, temporarily concealing all of said scenes save 5 one, illuminating said last-named scene, concealing that scene and illuminating another, and simultaneously setting up another scene at another point of said area and simultaneously obtaining scenic effects.
- 10 2. The method of changing scenic and setting effects in the presentation of plays and the like upon an immovable stage, which consists in setting up on said stage a plurality of sets so as to be simultaneously present 15 thereon, and adapted, when selectively illuminated, to present to view different scenic and setting effects, and successively and selectively illuminating and obscuring different ones of said sets to change the scenic and 20 setting effects presented to view.
3. In stage apparatus, the combination of a dark, light-absorptive curtain extending around the back and sides of a stage area, dark, light absorptive movable wings adapted 25 to conceal separate subdivisions of said area, and light-projectors positioned and adapted to illuminate one or another of said subdivisions, selectively, the wings used in connection therewith being moved to non- 30 obstructive positions.
4. In stage apparatus, the combination of a dark, light-absorptive curtain extending around the back and sides of a stage area, and movable wings, faced on at least one side 35 with dark material, projecting from points adjacent said curtain into said area, said wings being adapted to conceal separate subdivisions of said area.
5. In stage apparatus, the combination of a dark, light-absorptive curtain extending 40 around the back and sides of a stage area, and wings, pivotally mounted at points adjacent to said curtain, projecting from points adjacent said curtain into said area, said wings being adapted to conceal separate subdivisions of said area. 45
6. In stage apparatus, the combination of a dark, light-absorptive curtain extending around the back and sides of a stage area, and movable wings projecting from points 50 adjacent said curtain into said area, said wings being adapted to conceal separate subdivisions of said area, and said curtain being provided with openings through which scenery may be directly introduced into said subdivisions. 55
7. In stage apparatus, the combination of a dark, light-absorptive curtain extending around the back and sides of a stage area, and movable wings, projecting from points 60 adjacent said curtain into said area, said wings being adapted to conceal separate subdivisions of said area, and means operable from behind said curtain for moving said wings into and out of position for concealing 65 such subdivisions.

This specifications signed and witnessed
this 5th day of December, 1919.

EMILY ANN WELLMAN.

Certificate of Correction.

It is hereby certified that in Letters Patent No. 1,449,076, granted March 20, 1923, upon the application of Emily Ann Wellman, of New York, N. Y., for an improvement in "Methods of and Apparatus for Presenting Plays and the like," errors appear in the printed specification requiring correction as follows: Page 1, line 92, for the word "an" read *and*; page 2, line 129, claim 1, after the word "like" insert the words *and simultaneously obtaining scenic effects*; page 3, lines 8 and 9, same claim, strike out the words "and simultaneously obtaining scenic effects"; and that the said Letters Patent should be read with these corrections therein that the same may conform to the record of the case in the Patent Office.

Signed and sealed this 1st day of May, A. D., 1923.

[SEAL.]

KARL FENNING,
Acting Commissioner of Patents.
